(57) **CLAIM**

The ornamental design for an inhaler as shown and described.

DESCRIPTION

FIG. 1 is a front perspective view of the inhaler showing our new design and showing an inhaler cap in a closed position; FIG. 2 is a front view thereof; FIG. 3 is a back view thereof; FIG. 4 is a left side view thereof; FIG. 5 is a right side view thereof; FIG. 6 is a top view thereof; FIG. 7 is a bottom view thereof; FIG. 8 is a back perspective view thereof; FIG. 9 is a front perspective view of the inhaler of FIG. 1 showing the inhaler cap in an open position; FIG. 10 is a front view of the inhaler of FIG. 9; FIG. 11 is a back view of the inhaler of FIG. 9; FIG. 12 is a left side view of the inhaler of FIG. 9; FIG. 13 is a right side view of the inhaler of FIG. 9; FIG. 14 is a top view of the inhaler of FIG. 9; FIG. 15 is a bottom view of the inhaler of FIG. 9; and, FIG. 16 is a back perspective view of the inhaler of FIG. 9. The broken lines and areas in the drawings reflect environmental matter and form no part of the claimed design.

1 Claim, 16 Drawing Sheets
